UNITED STATES PATENT OFFICE.

ALEXANDER T. KASLEY, OF MOORE, PENNSYLVANIA, ASSIGNOR TO WESTINGHOUSE ELECTRIC & MANUFACTURING COMPANY, A CORPORATION OF PENNSYLVANIA.

BLOWING ENGINE.

Application filed July 18, 1924. Serial No. 726,775.

My invention relates to pumps, and more particularly to air pumps or compressors of the blowing-engine type, such as are used to supply air to the tuyères of blast furnaces. 5 It has for an object the provision of apparatus of the character designated in which control of the volume and pressure of the air pumped shall be accomplished without variation in speed of the apparatus and with- 10 out throttling of the air supply to the furnace.

Another object of my invention is to provide a blowing engine which is simple and reliable, and which may be driven by a 15 simple, constant-speed prime mover, such as an electric motor.

The requirements of blast furnace practice demand the supply of large volumes of air to the tuyères at a relatively low range of 20 pressures. Blowing engines are usually large, double-acting units, driven by slow-speed prime movers, necessary variations in pressure being secured by variation in the speed of the prime mover, which practice prohibits a drive by inexpensive, constant-speed electric motors.

By my invention, there is provided a device in which air is supplied by a relatively high speed, single-acting blower, or blowers 30 in which pressure control is independent of speed so that the blower may be driven by a constant-speed electric motor.

In the accompanying drawing, Fig. 1 is a view, partially in section and partially in elevation, of apparatus embodying my invention; Fig. 2 is a plan view of the apparatus shown in Fig. 1; Fig. 3 is a detail view of the gearing through which the apparatus is controlled; Figs. 4 and 5 are views similar 40 to Figs. 1 and 2 and illustrating a modified form of my invention in which two single acting cylinders are operated in tandem, and Fig. 6 is a detail view of the gearing of Figs. 4 and 5. Other structural features will be 45 apparent from the annexed specification.

Referring to Fig. 1, I show a blowing cylinder or tub 10, provided with a head 11, and in which a piston 12 is adapted to reciprocate. The piston 12 is driven by a

piston rod 13, connected to a crosshead 14, 50 which is actuated by a connecting rod 16 from a crank 17 on a power shaft 18. As shown, the power shaft 18 is driven by a constant-speed electric motor 19, but it is to be understood that any suitable source of 55 power may be used.

The cylinder 10 is provided exteriorly of its head with circumferentially arranged bearing lugs 21, having suitable bearings for screw shafts 22, surrounding the cylinder 60 10 in circumferentially spaced relation. The shafts 22 are supported on the blower frame by suitable thrust bearings 23, arranged on the blower frame, and by bearings 24, ar- 65 ranged in a pedestal 26. It is apparent that the bearings 24 may be thrust bearings if desired.

A portion of each of the shafts 22 is pro- 70 vided with a screw-threaded portion 27, adapted to cooperate with the lug nuts 28, secured to or integral with the cylinder 10 intermediate its length, and axially aligned with the bearing lugs 21. The shafts 22 constitute beams, supported by the bearings 23 and 24, and carrying the weight of the 75 cylinder 10 through the bearing lugs 21 and the lug nuts 28. As the shafts 22 are secured against longitudinal movement by the thrust bearings 23, it will be evident that rotation 80 of the shafts 22 will cause an axial movement 85 of the cylinder through the coaction between the screws 27 and the nuts 28. The limits of the stroke of the piston 12 are fixed, so that the axial movement of the cylinder 10 varies the position of the cylinder head 11 with respect to the piston, and therefore varies the percent clearance of the blower.

Each of the shafts 22 is provided near 90 its bearing 24 with a gear 29, by means of which it may be rotated. Each of the gears 29 mesh with a control gear 31, secured to a shaft 32, suitably journaled in the pedestal 26. In a duplex blower, the shafts 32 are provided with gears 33, intermeshing with a gear 34, adapted to be driven by a control 95 motor 36, as illustrated in Figs. 2 and 3. Rotation of the control motor 36, through the gear trains 34, 33, 31 and 29, and the

shafts 22, causes equal rotation of each of the screws 27, so that an equal axial movement of each of the cylinders 10 is secured.

The cylinder heads 11 and the pistons 12 are provided with suitable intake valves 37, and the cylinders 10 with discharge valves 38, through which the flow of air is controlled. The cylinder 10 may also be provided with relief ports 40 if desired. The exhaust valves 38 communicate with a discharge manifold 39, which in turn communicates by a telescopic joint 41 with a wind box 42. Air under pressure from the wind box 42 is conducted by suitable passages to the tuyères of the furnace being supplied, or to any other desired point of air consumption (not shown).

The operation of my device, as will be evident from the foregoing description, is as follows: Assume that the motor 19 is driving the blower at a constant rate of speed, and that the position of the cylinder 10 is such that the clearance between the head 11 and the piston 12 at its inner dead center is a minimum. Under these circumstances the piston displacement is practically equal to the cylinder volume, and the blower is delivering a maximum volume of air. If now the motor 19 be started to drive the gear train 34, 33, 31, 29, so that the shafts 22 and the screws 27 are rotated in the nuts 28, the cylinder 10 will be moved toward the left so as to increase the clearance between the head 11 and the piston 12. This decreases the ratio of piston displacement to cylinder volume, so that a less volume of air is pumped per stroke, and as the blower is running at constant speed, it consequently reduces the volume of air pumped per unit of time. The effective length of stroke of the piston 12 is also reduced as the clearance is increased by means of the relief ports 40, thus further reducing the volume of air pumped per stroke.

As the resistance to flow of the air, caused by the tuyères or other air consuming devices, remains unchanged, it follows that the pressure of air in the system will fall in proportion to the decrease in volume. In this manner regulation of the pressure and volume of air pumped is secured without variation in speed of the blower, and without throttling the air discharge.

Because my blower is adapted to deliver large volumes of air, the diameter of the cylinder 10 is large, and because of the comparatively high speed it is desirable that the piston 12 be as light as possible to reduce the strains incident to the inertia of a heavy piston. The piston is accordingly of thin construction, so that the buckling stress incident to the rapid changes in direction of the pressure on the piston 12 presents a serious problem. In Fig. 1 I

have illustrated a number of spaced brace rods 43, connected between points near the circumference of the piston 12, and the crosshead 14. By means of these rods the pressure exerted by the drive on the piston 12 is distributed over a considerable area thereof, instead of being concentrated as in the usual piston rod construction.

Referring to the form of my invention shown in Figs. 4, 5 and 6, I illustrate two aligned, single-acting cylinders at 50 and 51 respectively, these cylinders having their heads in juxtaposed relation and having a common piston rod 52, whereby they give the effect of a single double-acting cylinder, the cylinder 50 having a piston 53 and the cylinder 51 a piston 54.

The respective pistons are provided with inlet ports 55—55 and the respective heads with exhaust ports 56—56, the latter exhausting through telescoping joints 57—57 to an air manifold 58.

Longitudinally extending members 59, 60 and 61 pass through a central bearing pedestal 62 intermediate the cylinders 50 and 51 and further engage fixed portions of the blower through thrust bearings at 63 and 64. These members engage nuts on the cylinder 50 through left-hand threads and nuts on the cylinder 51 in right-hand threads, whereby rotation of the members 59, 60 and 61 in one direction causes the cylinders 50 and 51 to approach and rotation in the other direction causes the cylinders 50 and 51 to recede from each other.

The shafts 59, 60 and 61 carry pinions 65, 66 and 67 respectively at corresponding ends and these pinions mesh with a central gear 68 coupled to a worm wheel 69 meshing with a worm 70 coupled to a motor 71.

By suitable energization of the motor 71, the members 59, 60 and 61 may be rotated in either desired direction, thus adjusting the position of both the cylinders 50 and 51, changing their pumping capacity as will be evident from the foregoing description of the device of Figs. 1, 2 and 3.

Obviously, when using tandem cylinders as shown in Figs. 4 and 5, the cylinders may be made independently adjustable, but, in general, it is preferable to use coupled adjusting means as shown.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a pump comprising a piston adapted

- to reciprocate in a cylinder provided with a head, a plurality of nut members carried by the cylinder, screws adapted to operatively engage the nuts, and means including a gear 5 train to simultaneously rotate the screws, whereby the position of the cylinder may be adjusted with respect to the piston.
2. In a pump comprising a piston adapted to reciprocate in a cylinder provided with a head, means to adjustably position the cylinder with respect to the piston, discharge valves associated with the cylinder, a discharge conduit therefor, and means including a sliding joint for operatively connecting said valves to the conduit.
3. In a pump comprising a piston adapted to reciprocate in a cylinder provided with a head, means to adjustably position the cylinder with respect to the piston comprising 10 screw and nut gearing, discharge valves associated with the cylinder, a discharge conduit therefor, and means including a telescopic joint operatively connecting said valves to the conduit.
- 25 4. In a pump organization having a plurality of cylinders provided with heads, a piston adapted to reciprocate in each cylinder, means to adjustably position each cylinder with respect to its piston, and means to simultaneously actuate the said positioning means, whereby the several cylinders are given coincident movements.
- 30 5. In a pump organization having a plurality of cylinders provided with heads, a piston adapted to reciprocate in each cylinder, nut members carried by each cylinder, screws adapted to operatively engage the nuts, means including a gear train simultaneously actuating the screws to adjustably 35 position the several cylinders with respect to their respective pistons, valves associated with each of the cylinders, conduits adapted to communicate with the valves, and means including a telescopic joint associated with each cylinder operatively connecting the 40 conduits to the valves.
- 45 6. In a pump organization having a plurality of cylinders provided with heads, a piston adapted to reciprocate in each cylinder, means including a common crank shaft to actuate the pistons, a cross-head associated with each piston and connected thereto by diagonally disposed brace members, nut members carried by each cylinder, screws adapted to operatively 50 coact with the nut members and provided with thrust bearings to prevent their longitudinal movement, a gear adapted to actuate each screw, gears adapted to connect the first mentioned 55 gears in driving relation to form a gear train, means to actuate the gear train, valved discharge ports associated with each cylinder, a conduit therefor, and telescopic means connecting said ports to the conduit.
7. In a pump comprising a piston adapted to reciprocate in a cylinder, means for moving the cylinder with respect to the piston for varying the pressure of the fluid pumped, a fixed fluid discharge conduit, and means including a sliding joint operatively connecting the movable cylinder and the fixed conduit.
- 65 8. In a pump comprising pistons adapted to reciprocate in respective cylinders, means for simultaneously moving the cylinders with respect to their associated pistons for varying the pressure of the fluid pumped, a fixed fluid discharge conduit, and means including a sliding joint operatively connecting the movable cylinders and the fixed 70 conduit.
- 75 9. In a pump comprising pistons adapted to reciprocate in respective cylinders, means for co-extensively moving the cylinders with respect to their associated pistons for varying the pressure of the fluid pumped, a fixed fluid discharge conduit, and means 80 slidable upon the discharge conduit for operatively connecting the movable cylinders and the fixed conduit.
- 85 90 10. In a pump, the combination of a rod adapted to reciprocate and having a plurality of pistons secured thereto, a cylinder for each piston, means for adjustably positioning the cylinders with respect to their associated pistons, a fixed fluid discharge conduit, and means operatively connecting the respective cylinders and the fixed conduit.
- 95 100 11. In a pump, the combination of a rod adapted to reciprocate and having two pistons secured thereto a cylinder for each piston, means for co-extensively moving the cylinders with respect to their associated pistons for varying the pressure of the fluid pumped, a fixed fluid discharge conduit, and means operatively connecting the respective cylinders and the fixed conduit.
- 105 110 12. In a pump, the combination of a rod adapted to reciprocate and having two pistons secured thereto, a cylinder for each piston, said cylinders having head members disposed in juxtaposed relation, and means for altering the distance intervening between the cylinders, whereby the pressure of the fluid pumped is varied.
- 115 120 13. In a pump, the combination of a rod adapted to reciprocate and having two pistons secured thereto, a cylinder for each piston, said cylinders including end portions disposed in juxtaposed relation, and means for co-extensively moving the cylinders with respect to their associated pistons for varying the pressure of the fluid pumped.
- 125 14. In a pump, the combination of a rod adapted to reciprocate and having two pistons secured thereto, a cylinder for each piston, said cylinders having head members

disposed in juxtaposed relation, means for altering the distance intervening between the cylinders, a fixed fluid discharge conduit, and means operatively connecting the

for each piston, and means comprising screw and nut gearing for adjustably positioning the cylinders with respect to their associated pistons. 10

5 15. In a pump, the combination of a rod adapted to reciprocate and having a plurality of pistons secured thereto, a cylinder

In testimony whereof, I have hereunto subscribed my name this ninth day of July, 1924.

ALEXANDER T. KASLEY.
